UNITED STATES PATENT OFFICE.

ALBERT D. GROVER, OF NEW YORK, N. Y.

ATTACHMENT FOR BANJOS AND THE LIKE.

1,332,552.

Specification of Letters Patent.

Patented Mar. 2, 1920.

Application filed January 31, 1917, Serial No. 145,572. Renewed July 5, 1919. Serial No. 308,835.

To all whom it may concern:

Be it known that I, ALBERT D. GROVER, a citizen of the United States, and a resident of New York city, in the county of New York and State of New York, have invented certain new and useful Improvements in Attachments for Banjos and the like, of which the following is a specification.

10 My invention relates generally to musical instruments of the type represented by the banjo, and has for its object the provision of means readily attachable to the instrument for improving its tone quality.

15 It is well known that in damp weather the parchment head of a banjo becomes loose and flabby, owing to the absorption of moisture, thereby resulting in the production of a dull tone. In order to restore the bright

20 sharp tone of the instrument under these conditions, banjo players would heretofore tighten the head by turning down the bracket screws. However, it was found that this pulling-down process soon ruined the

25 head of the banjo. If the bracket screws were not loosened in time, the head would on the next dry day contract and often break.

By the use of my new device, which is 30 readily attachable to any make or style of banjo, the above disadvantages are overcome. The slackness in the head is taken up to a greater or less degree, as required, in such a way that the tone volume is increased.

35 Broadly speaking, my invention comprises a yieldable resilient member adapted to be connected with a fixed part of the banjo and bearing against the inner side of the head to exert an outward pressure thereon sufficient to take up the slackness in the 40 head. The point or place of contact between the pressure member and the head lies substantially only in that portion or area of the head which is between the neck and the

45 string-supporting bridge of the instrument. This is an important feature of my invention, for if that pressure contact is between the bridge and the tail-piece, as in the case of a ring, the result is a damped or muted 50 tone, instead of the sharp, increased tone caused by my invention.

In its preferred form, my new attachment comprises a spring bar connected midway of its ends with the dowel or stick of the 55 banjo and provided at its free ends with contact or connecting pieces which bear against

the inner side of the head. This contact between the head and the stick is adjustable so that the required amount of outward pressure on the head may be regulated, depending upon the slackness of the head. This particular form of attachment may be affixed to the banjo or removed therefrom in a few seconds, and no mutilation of any part of the banjo is necessary, as will hereinafter 60 65 more fully appear.

Referring now to the accompanying drawings which form part of this specification,

Figure 1 is a perspective view of the body of a banjo in inverted position, showing the 70 attachment in place.

Fig. 2 is a plan view of the attachment, with a portion of the banjo stick.

Fig. 3 is a cross-section on line 3—3 of Fig. 2.

Fig. 4 is a cross-section on line 4—4 of Fig. 2.

Fig. 5 is an inverted perspective view of the plate by means of which the spring bar of the preferred form of my attachment is 80 connected with the stick of the banjo.

Fig. 6 is a top plan view of a banjo provided with my new attachment, the latter being indicated in dotted lines.

Fig. 7 is a plan view of one end of a modified form of spring bar.

Fig. 8 is a section on line 8—8 of Fig. 7.

Fig. 9 is an end view of Fig. 8.

Fig. 10 shows a portion of a second modified form of spring bar, in which the bearing 90 portion is formed integral with the bar itself; and

Fig. 11 shows in cross-section an inverted view of a modified form of spring bar attached to the rim of the banjo.

Over the rim 1 of the banjo, or like instrument, is stretched the head 2 which is held in place by adjustable bracket screws 2^a. Through the center of the drum runs the dowel or stick 3 which is rigidly connected 100 with the neck 3^a. On the head is the string-supporting bridge 3^b, which is arranged near the tail piece 3^c.

The foregoing is the usual construction of instruments of this class and will be well understood by those skilled in the art.

My preferred form of attachment, as shown on Sheet 1 of the drawings, comprises a spring bar 4, made preferably of wood—such as maple. This bar is provided at the 110 middle with a pair of metal plates 4^a secured upon the opposite sides of the bar by means

of rivets 4^b or the like. At the ends of the spring bar 4 are connecting pieces 5 of any suitable construction. The particular form of connecting piece shown on Sheet 1 is one which I have found satisfactory in my own use. The particular form of connecting or contact piece is immaterial, so long as it establishes a firm and stable connection between the head and the bar 4, and provided further that the contact piece is not a ring or like member which extends across the space between the bridge and the tail piece. The use of such rings is old and the result is to dampen or mute the tone of the instrument, whereas my invention increases the tone volume.

The bar 4 is connected with the stick 3 by means of a plate 6 which is adapted to bear against the inner side of the stick 3 and thereby place the bar 4 under stress, so that the connecting pieces 5 exert an outward pressure on the head 2. The plate 6 is provided with adjustable screws 7 which bear against the bar 4 and may be adjusted to regulate the degree of pressure required to take up the necessary slack in the head 2. The plate 6 is also provided with pointed screws 8 and steady pins 9. As seen from Fig. 5, the pins 9 are arranged approximately in alinement with the adjustable pressure screws 7, while the pointed screws 8 are arranged approximately at right angles to the screws 7 and pins 9.

By means of the pointed screws 8, the spring bar 4 can be readily connected with the inner side of the stick 3. The points of the screws 8 sink into the wood of the stick 3 and thereby prevent the plate 6 from turning.

The steady pins 9 extend through correspondingly arranged openings 10 in the bar 4, and thereby hold the bar against a turning movement without interfering with its bending movement in exerting pressure against the head. As seen from Fig. 2, the openings 10 are preferably arranged in the median line of the bar 4, this median line being approximately the same as the section line 3—3 of that figure. In further defining the location and arrangement of the openings 10, I may say that the axes of these openings extend approximately at right angles to the plane of the bar 4 itself. Thus, in Fig. 3, the pins 9 extend in the direction of the axes of the openings 10.

In order to steady the connection between the bar 4 and the connecting pieces 5, the bar is provided with a pair of transverse grooves or slots 11, one near each end. To make the bar 4 reversible with respect to the supporting plate 6, I provide a second pair of grooves or slots 12 on the other side of the bar, so that the connecting or contact pieces may be properly positioned in either position of the bar 4. The grooves or slots

11 and 12 extend in a direction approximately at right angles to the length of the bar 4. In other words, the planes of said slots are approximately at right angles to the plane of the bar itself.

The operation of the attachment will be clearly understood from the foregoing description. By means of this attachment, a connection is established between the head 2 and a fixed part of the banjo, for exerting an outward pressure on the head to take up the slackness and increase the tone volume of the instrument. By adjusting the screws 7, or the screws 8, or both, the amount of pressure between the stick 3 and the head 2 may be regulated. In some cases but little slackness in the head 2 need be taken up, while in other cases the slackness might be much more and the same pressure would be obtained by simply adjusting the screws 7 and 8.

Another advantage of the adjustable screws 7 and 8 is that by means of them the distance between the bar 4 and the inner side of the stick 3 may be regulated to suit different styles or makes of banjos, in which the distance between the stick and the head varies.

It will be seen that my new attachment is readily attachable to the banjo and as readily removable therefrom, without injuring or mutilating any part of the banjo. The precise point or points of application of the pressure on the head are not material, provided that the pressure is applied substantially only in that portion of the head which lies between the neck and the bridge, for reasons already stated. The main advantage of my attachment is that it automatically maintains the head taut at all times. For instance, should atmospheric conditions so vary as to cause the head to expand or contract, the spring bar 4, or whatever spring mechanism may be used in any particular embodiment of my invention, will automatically adjust itself to maintain the tautness of the head. The player is thus assured that his instrument will always be in good playing condition, so far as the condition of the head is concerned. I have found in actual practice that the best results are obtained by arranging the bar 4 approximately across the center of the head, as shown in Figs. 1 and 6, although I do not consider this precise arrangement as absolutely necessary.

I have further found by actual trial that the most satisfactory results are obtained with a spring bar made of maple and having approximately the following dimensions: Length, seven and one-half inches; width in center, three-fourths of an inch; width at ends, seven-sixteenth of an inch; and thickness, one-eighth of an inch. I found that an arm of five thirty-seconds of

an inch thick was too stiff or rigid and would not give the proper amount of vibration, while an arm three thirty-seconds of an inch thick was found to be too weak to offer the required degree of resistance. I give these figures merely by way of illustration, and not in any sense as a limitation or restriction of my invention. It is better to have the bar a little too stiff than not stiff enough. It is obvious that different styles and sizes of banjos will require bars of different dimensions.

In Figs. 7, 8 and 9 I have shown another way of attaching the connecting pieces to the ends of the bar 4. In this instance, each end of the bar is provided with a slot 13 into which fits the reduced portion 14 of a connecting piece 5. Although the slot 13 extends in the direction of the length of the bar 4, the plane of that slot, like the planes of the slots 11 and 12, is approximately at right angles to the plane of the bar 4.

Instead of having a separate connecting piece at each end of the bar, the bar itself may be so shaped that it curves down at the ends to provide the desired contact with the head 2, as indicated at 15 in Fig. 10.

In Fig. 11, I have shown a spring bar 4^A attached to the rim 1 of the banjo by means of a screw 16. The free end of the bar 4^A is provided with an adjustable screw 17 having at its end a contact piece 18 which bears against the head 2. By adjusting the screw 17 the pressure on the head may be regulated to the desired degree.

The form of bar shown in Fig. 11 produces practically the same effect as the preferred form previously described. The first form is in my opinion preferable because it is more readily attached to the banjo, as well as removed therefrom.

In the broader aspect of my invention, it is not essential that the contact member, such as the connecting or contact piece 5, be at the end of a spring bar like that indicated at 4 or 4^A, but it might be placed directly under or near the stick 3, provided that the connection between the connecting piece and the stick 3 has the proper degree of resiliency. If this connection is absolutely rigid, or non-yielding, the characteristic sharp tone of the banjo will not be produced.

The reversibility of the vibrator arm 4 is of considerable advantage. Not only does this make it impossible to connect the bar 4 improperly with the support 6, but it increases the life of the bar. After the bar has been used for a certain length of time in the same position, it becomes set—that is to say, bent outwardly at the ends. When this occurs, the bar loses some of its power of resistance. Now, by simply reversing the bar face-wise with respect to the plate 6, its power of resistance is increased and it may

be continued in use until it becomes set again, whereupon it may again be reversed. By a face-wise reversal of the bar 4 with respect to the head 2, I mean such a reversal of position that what in Figs. 1 and 3 is shown as the upper face will become the lower face. In other words, again referring to Fig. 3, if the bar 4 were reversed face-wise with respect to the head 2, the connecting pieces 5 would at their outer ends enter the slots or grooves 12.

In the broad aspect of my invention, it will be understood that the slots or grooves 11, 12 and 13 are not necessary, especially where the contact pieces have a broad stable base. Thus, for instance, the contact pieces 5 will be held firmly pressed against the head 2 by the bar 4 without the use of the slots 11 and 12.

While I have herein described and illustrated certain specific constructions, I would have it understood that these specific embodiments have been set forth merely by way of illustration, and that the broad idea of my invention may be mechanically carried out in other ways than those set forth.

Having thus described my invention what I claim as new and desire to secure by Letters Patent of the United States, is:

1. In combination with a banjo or the like, a yieldable resilient member connected with a fixed part of the instrument, and contact means between said member and the head bearing against the inner side of the head to exert an outward pressure thereon under the influence of said spring member and thereby maintain the head taut at all times, the place of contact between said means and the head being away from the bridge and only in that portion of the head which lies between the neck and the bridge, whereby the tone volume of the instrument is increased.

2. In combination with a banjo or the like, a yieldable resilient bar connected with a fixed part of the instrument, and contact means at the free end of said bar bearing against the inner side of the head to exert an outward pressure thereon under the influence of said bar and thereby maintain the head taut at all times, the place of contact between said means and the head being away from the bridge and only in that portion of the head which lies between the neck and the bridge, whereby the tone volume of the instrument is increased.

3. In combination with a banjo or the like, a yieldable resilient bar connected with a fixed part of the instrument, and a readily detachable contact piece at the free end of said bar bearing against the inner side of the head to exert an outward pressure thereon under the influence of said bar and thereby maintain the head taut at all times, the place of contact between said contact

piece and the head being away from the bridge and only in that portion of the head which lies between the neck and the bridge, whereby the tone volume of the instrument 5 is increased.

4. In combination with a banjo or the like, a yieldable resilient bar connected at or near its center with the stick of the banjo and extending approximately at right 10 angles to the stick, and contact means at the free ends of said bar bearing against the inner side of the head to exert an outward pressure thereon under the influence of said bar and thereby maintain the head taut at 15 all times, the places of contact between said means and the head being away from the bridge and only in that portion of the head which lies between the neck and the bridge, whereby the tone volume of the instrument 20 is increased.

5. In combination with a banjo or the like, a yieldable resilient bar connected at or near its center with the stick of the banjo and extending approximately at right 25 angles to the stick, and a readily detachable contact piece at each free end of said bar bearing against the inner side of the head to exert an outward pressure thereon under the influence of said bar and thereby maintain the head taut at all times, the places of contact between said contact pieces and the head being away from the bridge and only in that portion of the head which lies between the neck and the bridge, whereby the 30 tone volume of the instrument is increased.

6. In combination with a banjo and the like, a yieldable resilient member connected with a fixed part of the instrument, contact means between said member and the head 40 bearing against the inner side of the head to exert an outward pressure thereon under the influence of said yieldable resilient member and thereby maintain the head taut at all times, the place of contact between said 45 means and the head being away from the bridge and only in that portion of the head which lies between the neck and the bridge, whereby the tone volume of the instrument is increased, and readily adjustable means 50 for regulating the pressure of said member on the head.

7. In combination with a banjo or the like, a support detachably connected with the stick between the bridge and the neck 55 of the instrument, a yieldable resilient bar detachably connected at or near its center with said support and extending approximately at right angles to the stick, and contact means between the ends of said bar 60 and the head for causing said bar to exert an outward pressure on the head and thereby maintain the head taut at all times, the places of contact between said means and the head being away from the bridge and 65 only in that portion of the head which lies

between the neck and the bridge, whereby the tone volume of the instrument is increased.

8. In combination with a banjo or the like, a support detachably connected with the stick between the bridge and the neck of the instrument, a yieldable resilient bar detachably connected at or near its center with said support and extending approximately at right angles to the stick, contact 70 means between the ends of said bar and the head for causing said bar to exert an outward pressure on the head and thereby maintain the head taut at all times, the places of contact between said means and the head being away from the bridge and only in that portion of the head which lies between the neck and the bridge, whereby the tone volume of the instrument is increased, and means for bodily adjusting 75 said bar relatively to the head to regulate the pressure thereon.

9. In combination with a banjo or the like, a plate non-rotatably connected with the stick at a point between the neck and the bridge, a yieldable resilient bar non-rotatably connected at or near its center with said plate member and extending approximately at right angles to the stick, means at the free ends of said bar bearing against the 90 head to exert an outward pressure thereon and thereby maintain the head taut at all times, the places of contact between said means and the head being away from the bridge and only in that portion of the head 95 which lies between the neck and the bridge, whereby the tone volume of the instrument is increased, and means carried by said plate for bodily adjusting said bar toward and away from the head to regulate the pressure 100 thereon.

10. In combination with a banjo or the like, a spring bar detachably connected at or near its center with the stick of the banjo and extending approximately at right angles 110 thereto at a point between the neck and the bridge, and a contact piece detachably connected with each end of said bar to bear against the head and thereby exert an outward pressure thereon, said bar being reversible face-wise with respect to the head and provided at its free ends with means whereby said contact pieces may be connected with said bar in either of its positions.

11. As a new article of manufacture, an 120 attachment for banjos or the like, comprising a supporting plate provided on one side with means adapted to extend into firm engagement with the banjo stick, a pair of steady pins extending from the opposite side of said 125 plate, a bar having openings or recesses approximately midway of its ends to receive said pins, and a pair of contact pieces adapted to be detachably connected with the free ends of said bar.

12. As a new article of manufacture, an attachment for banjos or the like, comprising a supporting plate having adjustable screws arranged in a line and adapted to make firm contact with the inner side of the banjo stick, a pair of pins extending from said plate in a direction opposite to said screws and arranged in a line approximately at right angles to the line of said screws, and a bar having openings or recesses at its center for receiving said pins. 60
- 5 13. As a new article of manufacture, an attachment for banjos or the like, comprising a supporting plate having a set of adjustable screws arranged in a line and adapted to make firm contact with the inner side of the banjo stick, a pair of pins extending from said plate in a direction opposite to said screws and arranged in a line approximately 65
- 10 at right angles to the line of said screws, a bar having openings or recesses at its center for receiving said pins, and a second set of adjustable screws extending from said plate in a direction to bear against said bar when 70
- 20 said plate and bar are assembled. 75
- 25 14. As a new article of manufacture, an attachment for banjos or the like, comprising a supporting plate having projections arranged in a line on one side of said plate and adapted to make firm contact with the banjo stick, pins extending from the other side of 80
- 30 said plate and arranged in a line approximately at right angles to the line of said projections, and a bar having openings or recesses to receive said pins. 85
- 35 15. As an attachment for banjos or the like, a new article of manufacture consisting of a flat spring bar provided with a pair of openings approximately midway of its 90
- 40 length and with a slot at each end, said openings being arranged approximately in the median line of the bar, the axes of said openings and the planes of said slots being approximately at right angles to the plane of the bar itself, substantially as and for the 95
- 45 purpose set forth. 100
- 50 16. As an attachment for banjos or the like, a new article of manufacture consisting of a flat non-metallic spring bar provided at the middle with a pair of metal plates secured upon the opposite sides of the bar, said plates and said bar being provided with 105
- 55 aligned openings arranged approximately in the median line of the bar and extending through the thickness of the bar, each end of said bar being provided with a slot or groove arranged in a plane approximately at right angles to the plane of the bar. 110
- 60 17. As an attachment for banjos or the like, a new article of manufacture comprising a plate having a pair of adjustable screws arranged in a line and extending at their tip ends from one face of said plate, a pair of pins extending from the opposite face of said plate and arranged in a line approximately 115
- 65 at right angles to said screws, and a second pair of adjustable screws extending from said plate at their tip ends in the same direction as said pins and arranged approximately in the line of said pins, substantially as and for the purpose set forth. 70
- 70
18. In combination with a banjo or the like, a contact member bearing against the inner side of the head at a place away from the bridge and only in that portion of the head which lies between the neck and the bridge of the instrument, and spring mechanism arranged between said member and a fixed part of the instrument for causing said member to exert an outward pressure on the head and thereby maintain the head taut at all times, whereby the tone volume of the instrument is increased. 80
- 75
19. As an attachment for banjos and the like, a new article of manufacture consisting of a resilient bar provided with a pair of openings approximately midway of its length, such openings being arranged approximately in the median line of the bar and the axes of said openings being approximately at right angles to the plane of the bar itself, substantially as and for the purpose specified. 90
- 80
20. In combination with a banjo or the like, a spring bar detachably connected at or near its center with the stick of the banjo and extending approximately at right angles thereto at a point between the neck and the bridge, and a contact piece detachably connected with each end of said bar to bear against the head and thereby exert an outward pressure thereon, said bar being reversible face-wise with respect to the head and adapted to hold said contact pieces firmly against the head in either of its positions. 100
- 85
21. As an attachment for banjos or the like, a new article of manufacture consisting of a flat non-metallic spring bar provided at the middle with a pair of metal plates secured upon the opposite sides of the bar, said plates and said bar being provided with aligned openings arranged approximately in the median line of the bar and extending through the thickness of the bar. 105
- 90
- 110
- In witness whereof, I hereunto subscribe my name this 30th day of January, 1917.
- ALBERT D. GROVER.
